[57] **CLAIM**

The ornamental design for a front bumper, as shown
and described.

DESCRIPTION

FIG. 1 is a front perspective view of a front bumper
showing my new design;

FIG. 2 is a front elevational view;

FIG. 3 is a rear elevational view;

FIG. 4 is a top plan view;

FIG. 5 is a bottom plan view;

FIG. 6 is a right side elevational view;

FIG. 7 is a sectional view taken along line VII—VII in
FIG. 2; and

FIG. 8 is a front perspective view thereof, it being
understood that the broken lines are for illustrative
purposes only.
